UNITED STATES PATENT OFFICE.

EDWARD J. DOLAN, OF PHILADELPHIA, PENNSYLVANIA, ASSIGNOR TO
WILLIAM HACKER, TRUSTEE, OF SAME PLACE.

CAN-ASSEMBLING MACHINE.

SPECIFICATION forming part of Letters Patent No. 375,053, dated December 20, 1887.

Application filed November 1, 1887. Serial No. 253,979. (No model.)

To all whom it may concern:

Be it known that I, EDWARD J. DOLAN, a citizen of the United States, residing at Philadelphia, in the county of Philadelphia and 5 State of Pennsylvania, have invented certain new and useful Improvements in Devices for Can-Assembling Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification. 15

My invention relates to can-making machinery, and has for its object to provide an attachment for machines of this kind which will facilitate the placing of the tops and bottoms upon the can-bodies while the same are in place upon the carrier during the process of manufacture.

To this end, and to such others as the invention may relate, the same consists in the peculiar combination and in the novel construction, arrangement, and adaptation of parts, 25 all as more fully described, shown in the drawings, and then specifically defined in the claims.

30 In the accompanying drawings, Figure 1 is a plan view of a portion of a can-making machine with my device for attaching the tops and bottoms. Fig. 2 is a side view of a can-body, showing the position of the top and bottom in first contact. Fig. 3 is a perspective view of the guides. Fig. 4 is a side view of a portion of a can-making machine and assembling attachment with one of the guides removed. Fig. 5 is a perspective view of the 35 guides.

40 Referring to the details of the drawings, A represents a section of the supporting-frame of an endless carrier for can-body blanks, the carrier proper consisting of a series of can-body clamps, B², pivotally connected together to form an endless carrier for the can-body blanks, such as is commonly used in connection with can-making machinery, for conveying the unfinished can-body blanks to that 45 portion of the machine at which the tops and bottoms of the cans are placed and afterward

secured in place upon the body of the can. The form of carrier, a section of which I have shown, is identical in construction with the form of carrier which I have shown and described in connection with my patent, No. 371,493, of October 11, 1887. As the endless carrier, however, forms no part of my present invention, which relates solely to the can-assembling attachment, which is equally well 55 adapted for use in connection with any of the various forms of endless carriers used in connection with can-making machinery, a detailed description of such carrier is deemed unnecessary in this connection. Within each of the 60 can-body holders B² is held a can-body blank B. 65 Secured to the sides of the carrier-frame, and with the free ends inclined at an angle outwardly and toward the rear of the machine, are the guides C C, each provided upon its 70 face adjacent to the carrier with a longitudinal slot or recess, C², of suitable width to receive and hold the blank ends of the cans. These guides are provided at their inner ends with extensions C³, which are arranged parallel with the line of travel of the endless carrier. 75 The blank covers or ends, the edges of which have been turned so as to form rims to embrace the ends of the can-body, are fed by the operator into the recesses C² at the ends 80 of the guides C.

D is a lever, the long arm of which is pivoted to a lug or ear, D², upon the outer face of the guide C, near its point of attachment to the carrier-frame. The lever is bent inwardly 85 at a point near its opposite end, and its free end is passed loosely through suitable openings at the sides of the guide C, as shown, and is held in position by means of the spring D³, one end of which is attached to the extension 90 D⁴ of the lever and its opposite end is secured to the carrier-frame, as shown.

The operation of the device is simple and will be readily understood. The tops and bottoms of the cans are placed by the operator 95 in the recesses at the free ends of the guides C, and as each top or bottom is placed in the recess the preceding top or bottom is forced along the recess until the same is filled along its entire length with blanks, each top or bottom, as it is forced into the end of the recess 100 by the operator, pushing the entire series pre-

ceding it forward within the slot. As each succeeding clamp carrying a can-body blank reaches the point at which the guides C are attached to the frame, the projecting ends of the blanks are brought into contact with the forward edges of the blanks for tops or bottoms, and with the continued forward movement of the carrier the ends of the can are brought into contact with the inwardly-projecting ends of the pressure-levers D, which serve to secure the same in place.

While I have shown my attachment as used in connection with that form of can-making machine in which the blank forming the body 15 of the can is carried within clamping devices secured to an endless carrier, I do not desire to limit myself to such use, as it is evident that it is equally well adapted for use in connection with any of the can-making machines 20 in which endless carriers are used.

It is also evident that, instead of providing guides for placing both tops and bottoms, if for any reason it should be desired, one of the guides may be dispensed with and but a single 25 one used.

Having thus described my invention, what I claim to be new, and desire to secure by Letters Patent, is—

1. The combination, with the moving can-body holder, of an inclined can-head guide-way extending in the same general direction as the travel of the can-body holder, as and for the purpose specified.

2. The combination, with the can-body holder, of an inclined can-head guide for the ends, and an extension to said can-head guide arranged parallel with the travel of the can-body holder, substantially as described.

3. The combination, with the can-body holder and the inclined can-head guide for the ends, of an extension to said can-head guide arranged parallel with the travel of the can-body holder, and a presser acting on the ends, as set forth.

4. The combination, with the can-body holder and the inclined can-head guide for the

ends, of an extension to said can-head guide arranged parallel to the travel of the can-body holder, and a spring-actuated presser arranged to act on said ends, as and for the purpose 50 specified.

5. The combination, with the can-body holder and the inclined can-head guide, of an extension to said can-head guide arranged parallel to the travel of the can-body holder, 55 and a presser operating at right angles to the travel of the holder, substantially as described.

6. The combination, with the can-body holder and the inclined can-head guide for the ends, of a pivoted presser located near the 60 terminus of said guide, substantially as and for the purpose described.

7. The combination, with the can-body holder and the inclined can-head guide for the ends, of a pivoted spring-actuated presser located near the terminus of said can-head guide, 65 substantially as and for the purpose specified.

8. The combination, with the can-body holder and inclined can-head guide for the ends, of a presser pivoted to said can-head 70 guide and operating at right angles to the travel of the can-body holder, substantially as and for the purpose specified.

9. The combination, with the can-body holder and the converging can-head guides 75 arranged upon opposite sides thereof, of pressers arranged at the termini of said guides and operating at right angles to the travel of the holder, as set forth.

10. The combination, with the can-body holder and the converging can-head guides arranged upon opposite sides thereof, of spring-actuated pressers arranged at the termini of said guides and operating at right angles to the travel of the can-body holder, as set forth. 85

In testimony whereof I affix my signature in presence of two witnesses.

EDWARD J. DOLAN.
